ATTORNEY

UNITED STATES PATENT OFFICE

171,844

HANDBAG

Harry De Satnick, Brooklyn, N. Y., assignor to Ascot Novelty Corporation, New York, N. Y., a corporation of New York

Application November 12, 1953, Serial No. 27,546

Term of patent 7 years

(Cl. D87—3)

To all whom it may concern:

Be it known that I, Harry De Satnick, a citizen of the United States, residing at Brooklyn, in the county of Kings, State of New York, have invented a new, original, and ornamental Design for a Handbag, of which the following is a specification, reference being had to the accompanying drawing, forming a part thereof.

Fig. 1 is a perspective view of a handbag showing my new design; and

Fig. 2 is a perspective view on a slightly larger scale of the handbag in its open position.

I claim:

The ornamental design for a handbag, as shown.

HARRY DE SATNICK.
